ACTUATOR FOR RECIPROCATING WELL PUMPS

Edgar W. Mong and William O. Anderson,
Los Angeles, Calif.

Application May 5, 1947, Serial No. 746,094

5 Claims. (Cl. 103—211)

1

This invention has to do with an actuator for reciprocating well pumps and it is a general object to provide a simplified, improved and practical construction for operating the reciprocating element of a well pump from an operating mechanism located in a derrick.

The ordinary or conventional pumping well involves a pump located in the bottom of the well and including a reciprocating element, a pump operating mechanism located in the derrick at the top of the well, and a string of sucker rods connecting the said mechanism and the reciprocating element of the pump. The string of sucker rods forms a heavy unit that sinks or moves down in the well by gravity after having been lifted by the action of the operating mechanism in the derrick. The usual string of sucker rods is made up of rod sections joined by threaded connections and consequently the handling of a string of rods, either to run it into the well or to remove it from the well, is a rather slow, costly operation, and furthermore, the rod sections themselves are somewhat difficult to handle since they are long ungainly members requiring rather careful handling.

It is a general object of the present invention to provide a construction whereby the usual string of sucker rods is replaced by an operating line in the form of a flexible cable which line can be easily and quickly handled as by means of a spool with consequent elimination of difficult time-consuming operations which attend the handling of an ordinary string of sucker rods.

Another object of the invention is to provide apparatus of the general character referred to wherein a spring is provided in the well adjacent the pump to serve as the means whereby the reciprocating element of the pump is returned or lowered after it has been lifted through the action of the operating mechanism in the derrick. By our present invention we provide an arrangement in which we employ a long, large, helical spring acting under compression so that it is long-lived and dependable in operation.

Another object of the present invention is to provide apparatus of the general character referred to wherein a spring abutment is detachably mounted in the lower end portion of the tubing to form an abutment for the upper end of the spring the abutment being detachable or removable so that when desired it is removable from the well with the removable pump parts and with the spring.

A further object of the present invention is to provide apparatus of the general character re-

2

ferred to involving simple, dependable means for removing the principal elements such as the spring and the spring abutment, so that such parts can be removed from the well whenever desired either for inspection, repair or replacement.

The various objects and features of our invention will be fully understood from the following detailed description of typical preferred forms and applications of the invention, throughout 10 which description reference is made to the accompanying drawings, in which:

Fig. 1 is a view showing the various essential parts of a pumping well, certain of the elements being shown in section. Fig. 2 is an enlarged 15 longitudinal sectional view of the structure occurring in the well at the pump or immediately above the pump, being a view taken substantially as indicated by line 2—2 on Fig. 1. Fig. 3 is a view of a portion of the structure shown in Fig. 2 20 showing the parts in a different position and showing a go-devil engaged with the mounting means to release it. Fig. 4 is an enlarged plan section taken as indicated by line 4—4 on Fig. 2. Fig. 5 is an enlarged transverse sectional view 25 taken as indicated by line 5—5 on Fig. 2, and Fig. 6 is a view similar to Fig. 3 showing a modified form of our invention.

Our present invention is concerned, generally, with well pumping equipment and more specifically 30 is applicable to certain standard elements of pumping equipment such as the ordinary or standard type of well pump and the ordinary well tubing as well as the ordinary pump actuating mechanism. The ordinary or conventional 35 type of well pump is located in the bottom of the well on the lower end of a string of tubing and it is characterized by a reciprocating part which is operated to gain the desired pumping action and this part may be either a reciprocating plunger or a reciprocating barrel. At the top of the well 40 or at the derrick the tubing is carried by a head and motion to be imparted to the reciprocating element of the pump is delivered by a pumping mechanism to a polish rod which is carried by 45 the head.

In the drawings we have illustrated various standard or conventional elements such as we have referred to above. For instance we show a typical derrick 10, a well casing 11 set in the well 50 and terminating at the derrick where it is equipped with a head 12. A string of tubing 13 is held by the head 12 and extends into the well through the casing and a pump 14 is carried at the lower end portion of the tubing. In the arrangement illustrated a perforated liner 15 de-

pends from the pump. The head 12 is shown passing a typical polish rod 16 and the polish rod is attached to an operating or pumping mechanism 17 to be reciprocated thereby. In the particular case illustrated we have shown a simple walking beam. However, it is to be understood that in practice I may employ any device or mechanism for reciprocating or stroking the polish rod.

The pump shown as carried by the tubing 13 involves a reciprocating element 18 designed to be operated or reciprocated to gain the desired pumping action and this arrangement of the pump is shown equipped or provided at its upper end with a valve cage 19.

The construction provided by the present invention involves, generally, a pump operating line 20 that extends through the tubing and connects the equipment at the top of the well with the reciprocating element 18 of the pump at the bottom of the well, a return spring 21 at or in the vicinity of the pump, an abutment 22 for the return spring, mounting means 23 for the abutment 22, operating means 24 for the means 23 controlled by the line 20 and operating means 25 for the means 23 independent of the line 20.

The operating line 20 that we provide is not a stiff or rigid structure such as a string of sucker rods, but rather is a flexible element preferably a flexible steel cable such that it can be handled when necessary by a reel or spool located at the derrick. The line 20 is shown attached to the lower end of the polish rod by a suitable coupling 30 and it extends down through the tubing to the vicinity of the pump where it is coupled to the reciprocating element 18 of the pump. In the particular case illustrated the lower end of the line 20 is joined or coupled to the element 18 of the pump by a rod 31 which may be considered a part of the means 24, as will be hereinafter described. If the member 20 is not a line or cable as above disclosed but is the usual sucker rod the return spring and the other elements that I have provided will function suitably as set forth.

The return spring is preferably a long, helical spring 21 carried in the tubing 11 between the upper end of the reciprocating element 18 and the abutment 22 which we locate in the tubing a suitable distance above the pump. The tubing is of substantial size making it possible to provide a large or adequate spring and the structure is such that the spring can be made of any desired length since the abutment 22 can be located any desired distance above the element 18 of the pump. In the particular case illustrated the spring 21 is shown as large in diameter as possible consistent with proper operation within the tubing and its lower end 33 is shown seated directly on the upper end of the reciprocating element 18, that is, on the upper end of the cage 19 which may be considered a part of the element 18. The upper end 34 of the spring 21 is shown in direct engagement with the abutment 22.

The abutment 22 is an annular member fitting the interior of the tubing with clearance and provided with a central opening or passage 35 slidably or freely passing the rod 31.

The mounting means 23 provided for the abutment 22 is, broadly, a means or structure whereby the abutment is releasably or detachably located in the tubing at the desired point. In the preferred form of the invention, as shown in the drawings the means 23 involves, gener-

ally, a seat member 36 fixed or stationary in the tubing, and a plurality of spring fingers 37 connected with the abutment and having lugs 38 that cooperate with the seat.

The seat member 36 may be in the form of a coupling that joins an upper tubing section X with a lower tubing section Y, in which case it is somewhat longer than an ordinary coupling and is provided intermediate its ends with an internal recess 40 which terminates at its lower end in an upwardly facing flat seat 41 and at its upper end in a downwardly facing inclined or pitched seat 42. Our construction is such that the seats 41 and 42 are spaced a substantial distance apart, that is, substantially farther apart than the ends 44 of tubing sections joined by an ordinary or standard coupling 45.

The fingers 37 are spring fingers, say for instance leaf springs, and in practice they may vary in number. In the drawings we have shown four symmetrically disposed fingers 37 and we have shown the fingers having their lower ends anchored or fixed to the abutment 22. Each finger is provided with an outwardly projecting lug 38 formed or shaped to have a downwardly facing shoulder 46 adapted to seat on and cooperate with the seat 41 and further provided at its upper end with an upwardly faced shoulder 47 which is pitched or inclined to correspond to and to seat on the seat 42.

The lugs 38 are of substantial length, that is, they are of greater extent than the space between the ends 44 of tubing sections joined by collars 45. However, they are short enough to engage in the recess 40 provided in the seat member 36. The spring fingers are so proportioned or shaped as to normally bear outwardly so that when the lugs 38 are moved to a position opposite the recess 40 the spring fingers move outwardly engaging the lugs in the recess. The shoulders 46 at the lower ends of the lugs cooperate with the seat 41 positively preventing downward movement of the fingers and consequently of the abutment 22 relative to the seat 36. The shoulders 47 engage and cooperate with the seat 42 preventing upward movement of the fingers, and consequently upward movement of the abutment member during normal operation of the pump. It is to be noted, however, that the seat 42 is beveled or pitched upwardly somewhat and the shoulders 47 are likewise pitched so that if excessive upward pressure is applied to the fingers or the lugs on the fingers, then the cooperation of the shoulders with the seat results in contraction of the fingers freeing the lugs from the seat and allowing the abutment member to move upwardly. This action or release of the fingers from the seat member only occurs, however, when upward pressure is applied, considerably in excess of that normally required during operation of the pump.

The means 24 provided for operating the mounting 23 to effect release of the lugs from the seat involves, generally, a bumper 50 movable to engage an element connected with the spring fingers so that upward force can be applied to the spring fingers from the rod. In the form shown in Figs. 1 to 5 of the invention the bumper 50 is an enlargement provided on the rod 31 which has its lower end joined to the reciprocating element of the pump while its upper end extends well above the seat 36 and is joined to the lower end of the line 20 by coupling 52. The bumper or projection 50 which may involve 70 equally spaced parts, as shown in Fig. 4, is such

as to be larger than the opening 35 through the abutment 22 so that if the rod 31 is moved upward far enough beyond the normal stroke of the pump the bumper engages the bottom of the abutment providing direct bearing engagement between the line or the rod 31 coupled to the line and the abutment 22. Under this condition the spring is under maximum compression. However, force may be communicated directly from the line to the abutment without depending upon communication through the spring and consequently a heavy upward pressure is applicable to the abutment to effect its release.

In Fig. 6 of the drawings we have shown a modified form of our invention wherein the means 24 above described is substantially the same but is applied in a different manner. In this application of the means 24 the bumper 50 is an enlargement provided on the rod 31 as above described and instead of engaging the abutment 22 it may freely pass it through an enlarged opening or passage 35a. The bumper 50 may pass up through, or it may pass down through the opening 35a without engagement of the bumper with the abutment. A collar 61 at the upper end of the spring assembly slidably passes the rod 31 and carries the upper ends of extensions 60 of the spring fingers. The extensions 60 as shown in the drawings are integral parts of the spring fingers and the parts may be proportioned so that when the rod 31 is moved upward beyond the normal stroke of the pump the bumper 50 engages the lower end of the collar 61. Further upward movement of the rod moves the collar upwardly putting the spring finger and the extensions under a tension strain which tends to flatten the spring fingers. With an upward pull on the lugs 38 and with the spring fingers in tension the lugs will readily be disengaged from the seat member. In this case the spring fingers operate under tension to release the lugs whereas in the first form of the invention described they operate under compression.

The means 25 provided for releasing the lugs 38 from the recess 40 is operable independently of the line 20 and, as shown in the drawings, it involves extensions 60 of the spring fingers extending upwardly and somewhat inwardly above the lugs 38. The upper ends of the extension 60 may be joined to the collar 61 slidably passing the rod 31. The operating member of the means 25 is a go-devil or weight 63 proportioned to slidably fit the interior of the tubing with suitable working clearance and provided with a central opening or passage 64 that will pass all obstructions on the line 20 as for instance couplings 52, or the like. The lower or operating end 65 of the go-devil is an annular part proportioned to engage the upwardly and inwardly extension parts 60 so that when the go-devil is dropped through the tubing the operating end 65 engages the extension parts 60 and wedges or moves them in to retract the lugs 38 from the recess 40.

In operating the apparatus that we have provided the parts are assembled as shown in the drawings and the parts are arranged and related so that under normal pumping conditions the reciprocating element 18 of the pump is given the full or desired stroke without the bumper 50 engaging the abutment 22. It will be understood that the pump element 18 or possibly other pump parts applied to the lower end of the line 20, as through the rod 31, may be lowered into

the well by means of the line with the spring 21, the bumper 22 and fingers 37 assembled therewith. The seat 36, which is a simple collar-like element, is the only part or element that is initially fixed or set in position and remains in position in the well.

As the assembly is lowered into the well the entire structure freely slides through the tubing until the lugs 38 come opposite the recess 40, 10 whereupon the spring fingers move the lugs out into seat engagement in the recess 40. With the lugs 38 engaged in the recess the abutment member 22 is set in operating position. As the pump is operated through reciprocation of the line 20 the line serves to lift the reciprocating element the desired distance and when upward strain is relieved from the line the spring 22 returns the reciprocating element to the down position. The action of the spring is of course 15 supplemented to a certain degree by the cable 20 which exerts a certain amount of downward pressure on the pump element 18 although not enough to cause the desired rate of operation of the pump.

20 When it is desired to remove the pump element or the part of the equipment that we have provided the line 20 may be moved up far enough to bring the bumper 50 into engagement with the abutment 22, or into engagement with the collar 61, as the case may be, and as upward strain is applied through the line the lugs 38 are disengaged from the seat 36 through the action above described, freeing the fingers which are on the abutment 22 so that the abutment 25 with the spring and the fingers attached are free to move up through the tubing. In place of the action just described or in conjunction with it we may drop the go-devil 63 into the tubing so that it engages the finger extensions 60 releasing the lugs 38 from the recess and freeing the structure for removal from the well.

Having described only typical preferred forms and applications of our invention, we do not wish to be limited or restricted to the specific details herein set forth, but wish to reserve to ourselves any variations or modifications that may appear to those skilled in the art and fall within the scope of the following claims.

Having described our invention, we claim:

50 1. A pump actuator for use with a well tubing carrying a pump with a reciprocating part operated by a line extending through the tubing including, a compression spring for insertion in the tubing to bear down on said part, an abutment for the upper end of the spring, a means releasably setting the abutment in the tubing above the pump including, a seat inserted in the tubing and a spring member connected with the abutment and releasably cooperating with the seat, means for releasing the first mentioned 55 means including a member slidably through the tubing to engage and deflect the spring member, and a bumper operated by the line to engage and move the abutment upwardly in the tubing.

60 2. A pump actuator for use with a well tubing carrying a pump with a reciprocating part operated by a line extending through the tubing including, a compression spring for insertion in the tubing to bear down on said part, an abutment engaged by the upper end of the spring, and a means releasably setting the abutment in the tubing above the pump including a seat coupling inserted in the tubing and having an inwardly facing recess, and a spring member rigidly connected with the abutment and projecting there-

from longitudinally of the tubing and having a laterally projecting lug engageable in the recess, the coupling and lug having cooperating inclined parts disengaged by upward pressure in excess of that required to operate the pump.

3. A pump actuator for use with a well tubing carrying a pump with a reciprocating part operated by a line extending through the tubing including, a compression spring for insertion in the tubing to bear down on said part, an abutment for the upper end of the spring, and a means releasably setting the abutment in the tubing above the pump including a seat coupling inserted in the tubing and having an inwardly facing recess, and a spring member connected with the abutment and having a projecting lug engageable in the recess, the coupling and lug having cooperating inclined parts disengaged by upward pressure in excess of that required to operate the pump and having cooperating parts positively preventing downward movement of the abutment relative to the coupling from the position where the lug is engaged in the recess.

4. A pump actuator for use with a well tubing carrying a pump with a reciprocating part operated by a line extending through the tubing including, a compression spring for insertion in the tubing to bear down on said part, an abutment engaged by the upper end of the spring, and a means releasably setting the abutment in the tubing above the pump including a seat coupling inserted in the tubing and having an inwardly facing recess with an inclined upper shoulder and a transverse lower shoulder, and a leaf spring rigidly connected to the abutment and extending therefrom longitudinally in the tubing, the spring having an inclined upper shoulder cooperatively engaging the upper shoulder of the

recess, having a transverse lower shoulder engaging the lower shoulder of the recess, and having an inclined face engageable by a go-devil to deflect the spring and simultaneously disengage the shoulders of the spring from the shoulders of the recess.

5. A pump actuator for use with a well tubing carrying a pump with a reciprocating part operated by a line extending through the tubing including, a compression spring for insertion in the tubing to bear down on said part, an abutment for the upper end of the spring, and a means releasably setting the abutment in the tubing above the pump including a seat coupling inserted in the tubing and having an inwardly facing recess with an inclined shoulder, and a plurality of circumferentially spaced leaf springs fixed to the abutment and each having an inclined shoulder cooperatively engaging the shoulder of the recess, a part engaged in the recess and positively preventing downward movement of the spring, an inclined face engageable by a go-devil to deflect the spring and disengage the shoulders.
